UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,161,880.

Specification of Letters Patent. Patented Nov. 30, 1915.

Original application filed September 15, 1910, Serial No. 582,214. Divided and this application filed May 7, 1913. Serial No. 766,145.

To all whom it may concern:

Be it known that I, OTTO PETERMANN, a citizen of the Republic of Switzerland, and a resident of Groton, county of Tompkins, and State of New York, have invented certain new and useful Improvements in Type-Writing Machines, of which the following is a full, clear, and exact description.

This invention relates more particularly to carriages for foldable visible typewriting machines, and is a division of my application Sr. No. 582,214, filed Sept. 15, 1910, now Patent No. 1,060,027, dated May 20, 1913.

One of the principal objects of the invention is to provide a typewriting machine in which the bed and the platen carriage or frame may be made from sheet metal and so formed as to permit the same to be properly held in position and adapted for use in connection with ball-bearings.

Another object of the invention is to provide a platen carriage having a part thereof serving to assist in the operation of the line-spacing mechanism.

A further object of the invention is to provide simple and efficient integral means forming a part of the carriage and bed whereby a ball-bearing may be interposed between the base of the carriage and the bed to adapt the carriage to run easily lengthwise of said bed.

A still further object of the invention is to provide a carriage which is simple, light and inexpensive to manufacture.

With these and other objects in view, the invention will be hereinafter more particularly described with reference to the accompanying drawings, which form a part of this specification, and will then be pointed out in the claims at the end of the description.

In the drawings, Figure 1 is an enlarged fragmentary section, partly in elevation, of one form of machine embodying my invention. Fig. 2 is a detail plan view of the carriage with the platen supported therein. Fig. 3 is a detail plan view of the carriage bed; and Fig. 4 is a fragmentary front elevation of the carriage showing how one end is made to provide means forming a part of the line-spacing mechanism.

While I show the invention as particu-

larly applicable to a typewriter in which the platen carriage is foldable or movable into compact relation to another part of the machine, as for example over the keyboard, in order that the machine may be made suitable for transportation purposes, and because of the fact that it is desirable in such machines that they be made light and strong, it will be understood that the invention is applicable to typewriting machines of various constructions.

The frame 10 may be made of sheet steel to a part of which the hangers 11 are secured. A type-bar 12 is pivotally held to each hanger 11 and this type-bar is operated by the usual key-levers and carries a type-head 13, the said type-head being adapted to be moved against the work sheet 14 held to the platen 14. The platen 14 is held to rotate in a carriage 15, the latter being formed of a single piece of sheet steel or other metal and adapted to move along a carriage bed 16. The carriage bed 16 is held by screws 17 or otherwise to arms or bars 18 forming a part of a foldable support 19. This support 19 has bars 20 on opposite sides of the machine and these bars 20 are pivoted, at 21, to the bars 18 to adapt the carriage to be folded forward into substantially overhanging relation to the keyboard. Each bar 20 is held to a post or slide 22. These slides are guided in their vertical movement by thimbles or brackets 23 located at the rear corners of the machine frame to adapt the support and carriage to be moved vertically by means of any suitable platen shift mechanism in order that the type-heads may have a plurality of characters thereon. The construction of the machine frame, the foldable support and the parts arranged in the machine frame form no part of the present invention and may be of any suitable construction.

The bed 16 along which the carriage is adapted to travel for letter spacing may be made of sheet steel or other metal which is pressed or formed in such a way as to make the same very light and strong and also serves as a guide for the carriage 15. This bed 16 has an upwardly turned flange 24 at one edge, and a flange 25 extending lengthwise of said bed

along the other edge, and said flange 25 is provided with a rib 26 near the bottom thereof which is formed by depressing said flange, and along the base of the bed are 5 longitudinally extending ribs 27, 28 and 29. These ribs form longitudinally extending channels, raceways or guideways 30 and 31 in which are balls 32. There are three balls shown, two arranged in the guideway 30 and one in the guideway 31 and these balls 10 are connected by a wire 32^a so that all of said balls move in unison, though other means than the special form of ball-bearing may be provided.

15 Above the bed 16 is the base 33 of the carriage 15. This base is provided with an upwardly extending flange 34 at one edge, and a flange 35 at its other edge, and said flange 35 is held against independent lifting movement by an angular bracket 36 secured to the wall or flange 25 of the carriage bed, while the upper edge of the flange 34 is engaged by a screw or other device 37 whereby the carriage may move along the 20 bed transversely of the machine in such a way as to be shifted with the bed 16. The carriage base 33 with its flanges 34 and 35 is located within the flanges 24 and 25 of the carriage bed and rests upon the balls 32 25 and is provided with a channel or guideway 38 extending lengthwise thereof and opposed to the guideway 30 of the bed 16. This guideway 38 is formed by depressing the base 33 of the carriage, as at 39, to form two ribs which are opposed to the ribs 28 30 and 29 of the bed 16 and which assists in properly guiding and holding the balls in place.

The carriage has integral end walls 40 and 41 which may be joined together by a transversely extending rod 42 at the rear thereof and one of said ends, as 40, has two outwardly extending integral arms 43, and an integral finger portion 44 which extends 45 upwardly to provide a fixed gripping part and which forms a part of the line-spacing mechanism. This finger portion cooperates with the pawl-carrying pivoted lever 45, shown in Fig. 2, and as the finger portion 50 44 is fixed with respect to the lever 45, the finger portion and lever 45 may be grasped by the hand and the former more readily operated than if the finger portion were dispensed with. The arms 43 have openings 46 55 formed by dies, or otherwise, and in said openings is held a rod 47 which serves as a pivot for the lever 45.

By forming the carriage in the manner shown, it will be evident that the said carriage with its finger portion 44 and the arms 43 serving as a support for the line-spacing lever may be made of a single piece of sheet metal in such a way as to be very light and dispenses with the necessity of forming 60 the frame of a plurality of parts, thus ma-

terially reducing the cost of manufacturing the same. It will be further evident that the carriage bed may be made of a single piece of metal and is so formed as to be very strong and light; that simple means is provided whereby ball-bearing raceways may be provided for the carriage; that simple and efficient supporting and guiding means is provided for the carriage; and that said parts may be readily made and assembled. 70

Having thus described my invention, I claim as new and desire to secure by Letters Patent:—

1. In a typewriting machine, a bed made 80 of sheet metal and having ribs pressed therefrom, a carriage provided with integral ribs lengthwise thereof and forming with the ribs of the bed ball-bearing channels lengthwise of the bed, and a ball bearing located in said channels. 85

2. In a typewriting machine, a bed made of sheet metal and having two sets of ribs pressed therefrom forming guideways, and a carriage provided with parallel ribs lengthwise thereof opposed to one set of ribs 90 of the base and forming with the bed a guideway adapted to serve as guide means, and a ball bearing located in said guideways. 95

3. In a typewriting machine, a bed made 95 of sheet metal and having two parallel sets of ribs located on opposite sides of the longitudinal center and pressed therefrom, and a carriage having a base provided with two parallel ribs lengthwise thereof which are 100 opposed to one set of ribs of the bed and having a straight part opposed to the other set of ribs, said ribs forming guideways, and bearing means located in said guideways. 105

4. In a typewriting machine, a bed made 105 of sheet metal having ribs pressed therefrom and forming a ball-bearing guideway lengthwise of the bed. 110

5. In a typewriting machine, a bed made of sheet metal having ribs pressed therefrom, and a carriage base coöperating with 110 said ribs to form ball-bearing channels lengthwise of the bed. 115

6. In a typewriting machine, a bed made of sheet metal having a plurality of sets of ribs lengthwise thereof pressed therefrom and forming guideways, and a carriage movable over said guideways and having two ribs forming a ball-bearing channel with a set of the ribs of the bed and having a flat 120 portion coöperating with another set to form a ball-bearing channel. 125

7. In a typewriting machine, a carriage having a base provided with upwardly extending flanges along its edge lengthwise 125 thereof and with end integral walls, one of said walls having integral outwardly extending arms and with an integral upwardly projecting finger portion, and a line-spacing member supported by said arms and 130

- having a projecting finger portion opposed to the projecting finger portion of the end wall to assist in the operation of said mechanism. 45
5. 8. In a typewriting machine, a sheet metal carriage having a base provided with integral end walls, one of said walls having an integral upwardly projecting finger portion, and line-spacing mechanism supported by one of the end walls and having a finger portion opposed to said carriage finger portion to assist in the operation of said mechanism. 50
10. 9. In a typewriting machine, a sheet metal carriage having a base provided with upwardly extending integral flanges and with integral end walls, and guiding means cooperating with said flanges. 55
15. 10. In a typewriting machine, a sheet metal carriage having a base provided with integral end walls, one of said walls having integral outwardly projecting arms, and line-spacing mechanism having a portion thereof supported by said arms. 60
20. 11. In a typewriting machine, a sheet metal carriage having a base provided with integral end walls, one of said walls having means to support line-spacing mechanism and an integral upwardly projecting finger portion located adjacent to said mechanism and adapted to assist in the operation of the line-spacing mechanism. 65
25. 12. In a typewriting machine, a sheet metal carriage having a base provided with upwardly extending flanges and with end walls, one of said walls having integral arms, and line-spacing mechanism having a part supported by said arms. 70
30. 13. In a typewriting machine, a sheet metal carriage bed, a carriage having end walls, one of said walls having integral outwardly extending arms and having an integral finger portion adjacent to said arms, 75
35. 14. In a typewriting machine, a sheet metal bed having flanges along the edges thereof, and a sheet metal carriage having integral end walls and a base also provided with flanges at the edges thereof, and means for guiding the flange edges of the carriage. 80
40. 15. In a typewriting machine, a sheet metal bed provided with upwardly extending flanges along the edges thereof, a sheet metal carriage having integral end walls provided with a base also provided with flanges at the edges thereof fitting within the flanges of the bed, and means mounted on the flanges of the bed for guiding the flange edges of the carriage. 85
45. 16. In a typewriting machine, a sheet metal carriage provided with flanges along the edges longitudinally thereof and integral end walls, and means for guiding the flange edges of the carriage. 90
50. 17. In a typewriting machine, a bed, and a carriage supported over said bed and comprising a base having flanges along the edges thereof, integral end walls extending upwardly from the base, an integral finger portion formed as a part of one end wall, and a platen supported in the end walls. 95
55. 18. In a typewriting machine, a bed, and a sheet metal carriage supported over said bed and comprising a base having upwardly extending flanges along the edges lengthwise thereof, guiding means for the carriage, integral end walls extending upwardly from the base, and a platen supported in the end walls. 100
